CLAIM

The ornamental design for a pair of wireless earbuds, as shown and described.

DESCRIPTION

FIG. 1 is a front perspective view of a pair of wireless earbuds, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the pair of wireless earbuds inside a case.

The broken lines showing a case in FIG. 8 are for the purpose of illustrating environment only and form no part of the claimed design.

The broken lines in the drawings depict portions of the pair of wireless earbuds that form no part of the claimed design.
